BENDING MACHINE

Richard W. Broomham, Detroit, Mich., assignor
to Motor Products Corporation, Detroit, Mich.,
a corporation of New York

Application November 15, 1937, Serial No. 174,701

1 Claim. (Cl. 153—40)

This invention relates generally to bending machines and refers more particularly to apparatus for fashioning strip stock to a predetermined longitudinal contour.

5 It is one of the principal objects of this invention to provide a compact, inexpensive bending machine composed of a relatively few simple parts and capable of rapidly bending strip stock to a predetermined longitudinal contour without wrinkling, or overstressing the stock.

A further object of this invention resides in the provision of a bending machine wherein a straight strip of stock preformed to a predetermined cross sectional contour may be longitudinally bent to form a closed frame of the desired size in one operation without interfering with the cross sectional contour of the strip.

The foregoing, as well as other objects, will be made more apparent as this description proceeds, especially when considered in connection with the accompanying drawings, wherein:

Figure 1 is a plan view of a machine constructed in accordance with this invention;

Figure 2 is a longitudinal sectional view taken substantially on the plane indicated by the line 2—2 of Figure 1;

Figure 3 is a cross sectional view taken substantially on the plane indicated by the line 3—3 of Figure 1;

30 Figure 4 is a sectional view taken substantially on the plane indicated by the line 4—4 of Figure 1;

Figure 5 is a side elevational view of a closed frame fashioned from a straight strip of stock by the machine forming the subject matter of this invention;

Figure 6 is a cross sectional view taken substantially on the plane indicated by the line 6—6 of Figure 5;

40 Figure 7 is a sectional view taken substantially on the line 7—7 of Figure 4; and

Figure 8 is a sectional view taken substantially on the line 8—8 of Figure 1.

The machine selected herein for the purpose of illustrating the present invention is designed to form garnish molding frames of the type used in association with the window openings in motor vehicle bodies, although it will be understood as this description proceeds that the machine may be advantageously used in any case where it is desired to longitudinally bend a strip of stock having a predetermined cross sectional contour.

In general, a form or templet frame 10 is secured to a revoluble support 11 for rotation therewith as a unit, and a bending shoe 12 is

supported opposite the templet frame 10 in cooperative relation therewith. Upon reference to Figure 2, it will be noted that the templet frame 10 is formed with a continuous recess 13 in the outer surface thereof having a cross sectional 6 contour predetermined to cooperate with the shoe 12 in effectively supporting the strip to be bent throughout the cross sectional area of the latter. In the present instance, the cross sectional area of the strip of stock is such as to require the shoe 12 to be telescoped into one end of the stock, and this operation is effected before the straight strip of stock is introduced into the machine.

After the shoe 12 has been inserted in one end portion of the strip of stock, the latter is placed in the recess 13 of the templet frame 10 at the substantially straight side A of the latter, and the free end of the strip of stock beyond the shoe is clamped to the templet frame by means of the clamp 14. Prior to actually clamping the strip of stock to the templet frame 10, the shoe holder 15 is placed in operative relation to an air cylinder 19 which serves to yieldably maintain the shoe 12 in clamping engagement with the strip of stock on the templet frame throughout rotation of the latter about the axis of rotation of the support 11. The piston in the air cylinder has sufficient travel to insure engagement of the shoe with the templet, irrespective of the irregular contour of the latter and the line of action of the piston is such that the clamping pressure is applied to the shoe 12 at a point laterally offset from the axis of rotation of the templet in a direction opposite the direction of rotation of the templet. As a result, the bending pressure exerted by the shoe on the stock produces a force component which extends in a direction opposite the direction of rotation of the templet frame 35 and insures effectively bending the stock around the frame.

It will, of course, be understood from the above that the piston in the air cylinder moves axially of the cylinder during rotation of the irregular 45 templet frame 10 relative to the shoe 12 and, in order to effect a substantially straight line movement of the piston, the shoe holder is assembled on the free end of an arm 16 having the opposite end pivotally supported to provide for swinging 50 movement of the arm in the plane of rotation of the templet frame. The radius of the arc is relatively large as compared to the extent of travel of the shoe 12 so that outward movement of the shoe 12 by the templet frame is transferred 55

in a substantially straight line to the piston in the air cylinder 19.

It may also be briefly pointed out at this time that the shoe holder has a readily detachable connection with the arm 16 in order to permit the same to be quickly assembled with and removed from the machine. In this connection, it will be noted that the outer side of the shoe holder has a vertically extending V-shaped groove 17 therein adapted to receive a pin 18 carried by the swinging end of the arm 16. The bottom of the groove is transversely curved and the pin 18 is cylindrical so as to permit limited angular adjustment of the shoe 12 relative to the arm 16 during the bending operation.

The full line position of the templet frame 10 in Figure 1 of the drawings illustrates the starting position and, as the templet frame is rotated from this position to the dotted line position thereof illustrated in the same figure, the strip of stock is bent to the contour of the templet frame. The machine is automatically stopped in the dotted line position of the templet frame by means of the switch 20 and, after the clamp 14 is released, the bent strip is removed from the templet frame with the shoe in assembled relation therewith. The shoe is then removed from the finished strip and assembled with another straight strip of stock in readiness for the next cycle of operation. It will, of course, be understood that prior to assembling the straight strip of stock in the machine, the latter is again started to locate the templet frame 10 in the full line position thereof, whereupon a second switch 22 operates to automatically stop the machine.

Referring now more in detail to the particular construction of the machine and with special reference to Figure 2, it will be noted that the reference character 25 designates a table mounted upon a suitable frame structure 26 which, in turn, is secured to a base plate 27. The table 25 is formed with a vertically extending opening 28 therethrough for receiving a vertical shaft 29 having axially spaced portions journaled in bearings 30 supported in the opening 28 of the table. The lower end of the shaft 29 is connected to the power take-off shaft 31 of a suitable speed reducer 32 by means of a flanged coupling 33, and the upper end of the shaft is secured to a revolvable base plate 34. The base plate 34 is located in a recess 35 formed in the top surface of the table 25 and is secured to the templet frame support 11 for rotating the templet frame about the axis of the shaft 29.

The power take-off shaft 31 of the speed reducer 32 for rotating the shaft 29 is connected through the medium of suitable reduction gearing (not shown) to the driven shaft 38 of the speed reducer, and the latter, in turn, is coupled to the drive shaft 39 of a suitable prime mover unit 40. The prime mover unit 40 includes an electric motor 41 arranged in an electrical circuit which is adapted to be closed by a manually operable switch conveniently located on the machine. The electric circuit forms no part of the present invention and, with the exception of the stop switches 20 and 22, is not shown herein. As previously pointed out, the switch 22 opens the circuit to the electric motor 41 upon completion of the bending operation, and the switch 22 functions to open the circuit to the electric motor 41 after the form 10 has returned to its original starting position. In other words, when the templet frame 10 has been advanced to the dotted line position shown in Figure 1, the switch 20 is

tripped to open the circuit to the motor 41 and thereby discontinue rotation of the form 10. The completed strip is then removed from the machine and the circuit to the motor 41 is again closed to advance the templet frame 10 to its full line position, shown in Figure 1. At this time, the switch 22 is automatically tripped to again open the circuit to the motor 41 and thereby discontinue further advancement of the templet frame until the circuit is closed by the manually operable switch (not shown) on the machine frame. In the present instance, the switch 20 is tripped by means of an arm 42 mounted on the flanged coupling 33 for angular adjustment, and the switch 22 is tripped by an arm 43 also mounted on the flanged coupling 33 for angular adjustment. It will, of course, be understood that the two arms are so positioned as to stop the machine in the positions previously defined.

Upon reference to Figures 2 and 3, it will be noted that the table 25 is formed with a longitudinally extending groove 44 in the top surface thereof, and this groove extends radially outwardly from the axis of rotation of the templet frame 10. Mounted in the groove 44 for adjustment 25 toward and away from the templet frame 10 is a bracket 45 having an upwardly extending portion 46 at the outer end thereof for attachment to the adjacent end of the air cylinder 19. The air cylinder 19 is provided with lugs 48 extending beyond the outer end of the air cylinder and pivotally connected to the portion 46 of the bracket by means of a vertical pin 49. The arrangement is such as to permit swinging movement of the air cylinder 19 relative to the bracket 35 45 in a substantially horizontal plane.

A piston 50 is reciprocably mounted in the air cylinder and is operatively connected to the free end of the arm 16 by means of a rod 51 which extends through the inner end of the air cylinder 19. Upon reference to Figure 4, it will be noted that the extreme inner end of the rod 51 extends between a pair of vertically spaced ears 52 projecting outwardly from the free end of the arm 16 and pivotally connected to the rod 51 by 45 means of a vertical pin 53.

As shown in Figure 1, the arm is pivotally connected, as at 54, to a bracket 55 which is bolted, or otherwise fixedly secured to the table 25 of the machine. The distance between the pivot pin 54 and the pivotal connection 53 between the free end of the arm and air cylinder is so determined that the arm moves throughout an arc of substantial radius by the templet frame 10 as the latter is rotated about the axis of the shaft 29. In other words, the swinging arm 16 transfers the reactionary forces exerted on the shoe 12 by the templet frame 10, to the piston 50 in a substantially straight line and thereby minimizes the stresses applied to the air cylinder 19. Attention is also called to the fact at this time that the line of action of the piston 50 is inclined in the direction of outward movement of the arm 16 from the neutral position of the latter and applies the yielding pressure against the templet frame at a point laterally offset from the axis of rotation of the templet frame in a direction opposite the direction of rotation of the latter. This arrangement assists in securing substantially straight line action of the piston 70 50 and also assists in bending the strip stock around the templet frame during rotation of the same.

Referring again to Figure 4 of the drawings, it will be noted that the shoe holder 15 is adapted 75

to be supported between vertically spaced furcations 57 extending inwardly from the free end of the arm 16 and having the vertical pin 18 extending therebetween. The pin 18 engages the bottom of the groove 17 formed in the outer side of the shoe holder and provides a fulcrum about which the shoe may oscillate during the bending operation. The inner side of the shoe holder 15 is channeled, as at 58, for receiving the shoe 12 and the latter is removably secured in the channel by suitable fastener elements, such as tap screws. The shoe is, of course, supported in such a position that it will engage in the recess 13 in the templet frame and will cooperate with this recess to effectively support the strip throughout its cross sectional area during the bending operation.

From the above description, it will be noted that the shoe follows the longitudinal contour 20 of the templet frame as the latter is rotated about the axis of the shaft 29 and, in addition, exerts a clamping pressure against the strip throughout the entire bending operation. It will also be apparent that the strip may be accurately bent 25 to form a closed frame of predetermined dimension and that the cross sectional contour of the strip is preserved during the bending operation.

What I claim as my invention is:

In a machine for bending a strip of stock to a predetermined longitudinal contour, a templet having a working surface corresponding in shape to said predetermined longitudinal contour, an arm supported for swinging movement in the plane of the templet toward and away from the working face of the latter, fluid pressure operated means including a cylinder pivotally supported for swinging movement in a plane substantially parallel to the plane of the templet, a piston reciprocably mounted in the fluid pressure cylinder for swinging movement with the latter and connected to the swinging end of the arm to urge the latter end of the arm toward the working face of the templet, a shoe having one face engageable with the strip of stock and having a substantially V-shaped groove in the opposite face fulcrumed on and disconnectedly engaging the swinging end of the arm for movement by the piston into clamping engagement with the strip of stock, and means for moving the templet relative to the shoe to effect a bending of the stock to the contour of the working face of the templet. 5 10 15 20 25
